UNITED STATES PATENT OFFICE.

MAE W. ELLS, OF ADRIAN, MINNESOTA.

CORSET-STAY BRACE AND ABDOMEN SUPPORT.

Application filed October 17, 1921. Serial No. 508,134.

To all whom it may concern:

Be it known that I, MAE W. ELLS, a citizen of the United States, residing at Adrian, in the county of Noble, State of Minnesota, have invented certain new and useful Improvements in Corset-stay Braces and Abdomen Supports; and I do hereby declare the following to be a full, clear, and exact description of the invention, such as will enable others skilled in the art to which it applies to make and use the same.

This invention relates to new and useful improvements in corsets and particularly to attachments therefor.

One object of the invention is to provide an attachment for a corset by means of which the stays will be held in proper position and prevented from bulging outwardly.

Another object is to provide an attachment for a corset which serves not only to maintain the ends of the stays in position, but serves as an abdominal retainer or support.

Another object is to provide a device of this character which can be easily and quickly secured to any corset now on the market without modification to the corset.

Other objects and advantages will be apparent from the following description when taken in connection with the accompanying drawing.

In the drawing:

Figure 1 is an elevation of a corset showing the invention applied thereto.

Figure 2 is an enlarged vertical sectional view through one of the front stays of the corset and the attachment, on the line 2—2 of Figure 1.

Figure 3 is a sectional view, enlarged on the line 3—3 of Figure 1, running longitudinally of the attachment.

Referring particularly to the accompanying drawing, 10 represents a corset which has the front stays 11 and 12 which carry the fastening studs and loops 13 and 14, respectively. The lower ends of these stays are disposed at the points 15, which is a distance above the lower end of the corset. This lower end portion of the corset is flexible and forms the skirt of the corset, the same being provided with the fasteners 13' and 14', at the closure.

Secured to one side of the closure of the corset, adjacent the stay 11, is a piece of strong fabric 16, the edge adjacent the stay being provided with a series of eyes 17 secured thereto. Secured to the other side of the closure of the corset, and at a distance rearwardly of the stay 12, is a strip 18 of fabric of the same width as the strip or piece 16, but of greater length. The longitudinal center of this strip 18 is disposed on the line of the lower ends of the stays 11 and 12, so that the lower half of the strip lies on the skirt of the corset. The strip 18 is preferably formed from two or more layers of fabric, and between these layers, and in the center of the strip, is secured a metal plate 19, the same being of considerably smaller dimensions than the strip. The metal plate is so disposed within the strip 18 that one half of it is disposed above the stay line and the other half below said line, so that the lower ends of the stays rest against the plate. It will be noted that the larger fabric member 18, when drawn across the front of the corset, and hooked to the eyes 17 of the member 16, by the hooks 20, carried by the free edge of the member 18, disposes the metal plate 19 directly against the lower ends of the stays 11 and 12, thus holding these stay ends from bending outwardly from the front of the corset, and also holding the stays so that they will not bulge outwardly.

It will be further noted that the lower half of the attachment lies below the stay line, and is flexible, so that when properly hooked together across the front of the corset, the attachment serves to hold the abdomen in and up, thus producing an effective support for the abdomen.

While I have illustrated the device as applied to the front of the corset, it will be readily understood that the attachment may be used with equal effectiveness at the rear of the corset, and on the stay line, to hold the rear stays against bending.

What is claimed is:

The combination with a corset having a front closure and stays terminating at a line above the lower end of the corset, of an attachment therefor comprising a short strip of fabric secured to the corset at one side of the closure adjacent the stay, said strip

extending in parallel relation to the stay and provided with eyes, a longer strip of fabric secured at one end to the corset at the other side of the closure and at a distance rearwardly of the stay and provided with hooks for engagement with the said eyes, said longer strip extending across the closure, and a stiff plate secured to the cen-

ter of the longer strip and arranged to lie across the ends of the engaged stays. 10

In testimony whereof, I affix my signature, in the presence of two witnesses.

MAE W. ELLS.

Witnesses:

LELIA H. JONES,
G. V. MURKEY.
